UNITED STATES PATENT OFFICE.

WILLIAM D. KLIPFEL, OF CHICAGO, ILLINOIS.

AUTOMATIC AIR-VALVE.

SPECIFICATION forming part of Letters Patent No. 655,785, dated August 14, 1900.

Application filed January 17, 1900. Serial No. 1,752. (No model.)

To all whom it may concern:

Be it known that I, WILLIAM D. KLIPFEL, a citizen of the United States, residing at Chicago, in the county of Cook and State of Illinois,

5 have invented certain new and useful Improvements in Automatic Air-Valves, of which the following is a specification.

The object of this invention is the production of an air-valve, automatic in its action, 10 adapted to cause the discharge of the air which collects in steam-radiators.

The valve herein shown and described is 15 adapted particularly to those heating systems wherein an exhaust-fan or steam-jet is employed to draw away from the valve the cold air or steam discharged therefrom.

In the accompanying drawings, Figure 1 is 20 a central vertical section through my improved air-valve. Fig. 2 is a horizontal section on dotted line xx of Fig. 1.

Like letters of reference indicate corresponding parts throughout both views.

In the construction of this air-valve I provide the body portion A of cylindrical form, 25 which body portion has the interior steam-chamber A' and a steam-inlet pipe A², communicating with said chamber. The outer end of said inlet-pipe A² is externally screw-threaded to provide a means of connection

30 between the air-valve as a whole and the radiator, (not shown,) and also to provide a communication between the steam-chamber A' and the interior of the radiator-pipes. A central opening A³ in the upper wall of the 35 steam-chamber A' provides the means of escape for the cold air which collects in the radiator-pipes and enters the steam-chamber A'. This opening A³ has a closure, to be later described herein, actuated by the expansion

40 and contraction of the material of which it is composed. The lower end of the body portion A contains the discharge-chamber A⁴, and the wall A⁵, which separates said discharge-chamber from the steam-chamber A', 45 has a screw-threaded opening A⁶, closed by the correspondingly-screw-threaded cup A⁷. A pencil A⁸, preferably made of a vulcanized rubber composition and slightly tapered at

50 its upper end to fit into the opening A³, is secured in the cup A⁷. The pencil A⁸ is adjusted with relation to the opening A³ by turning the cup A⁷ in its supporting screw-

threads. The lower exterior portion of the body A is screw-threaded to afford a means for the attachment of a cold-air exhaust, to 55 be later described herein.

B is a discharge-duct, the walls of which duct are formed integral with the walls of the body portion A. This duct communicates at its lower end with the discharge-chamber A⁴ 60 and at its upper end through the opening A³ with the steam-chamber A'.

C is an internally-screw-threaded coupling having an annular shoulder C' near its upper end. The coupling C is adapted to fit against 65 the lower end of the body portion A of the air-valve, and to make a tight joint between said body portion and the coupling C their adjacent faces are ground together. A sleeve C², internally screw-threaded to correspond 70 to the threads upon the lower part of the body portion A, is adapted to hold said coupling in engagement with said body portion, so that the interior of the coupling opens into the discharge-chamber A⁴. 75

While I have described the pencil A⁸ as being made of a vulcanized rubber composition, it may be of copper or other metal, though on account of the expansive qualities of the vulcanized composition the latter is more desirable than metal. 80

The operation of this air-valve is as follows: The pipe A² is connected with the interior of a steam-radiator and the coupling C placed in connection with means for exhausting a 85 portion of the air from the discharge-chamber A⁴, which means may consist of a steam-jet. The adjusting-cup A⁷ is turned in its screw-threads so that the end of the pencil A⁸ nearly closes the opening A³. Steam is 90 admitted to the radiator, driving the cold air before it into the steam-chamber A'. The exhaust, acting through the coupling C, the discharge-chamber A⁴, and the duct B, draws the cold air from the steam-chamber A' 95 through the opening A³ until all the cold air has been exhausted from the radiator-pipes. After the cold air has been expelled steam enters the chamber A', heating the pencil A⁸, causing it to expand sufficiently to close the 100 opening A³, thus preventing the escape of steam through the discharge-duct B. When from any cause cold air accumulates in the radiator-pipes and the temperature within

the steam-chamber A' falls sufficiently to cause the pencil A⁸ to contract, the opening A⁸ is uncovered, and the cold air is withdrawn from the radiator-pipes by means of the reduced air-pressure in the discharge-chamber A⁴, permitting steam again to enter the steam-chamber A', expand the pencil A⁸, and thus close the opening A⁸, which latter remains closed until the pencil again contracts and opens the port A⁸.

I claim as my invention—

In an automatic air-valve, a valve-body composed of one integral piece provided with an inlet-opening, a cylindric central steam-chamber having communication with said inlet-opening, a discharge-chamber axially aligned with said steam-chamber and having a screw-threaded opening communicating

therewith, a discharge-duct formed within the walls of said steam-chamber extending at the top and the side thereof and communicating with the interior of said discharge-chamber, an escape-opening communicating between the upper part of the steam-chamber and the discharge-duct, which escape-opening is aligned with said screw-threaded opening; in combination with a pencil of material expandible by heat; and a cup-shaped holder for said pencil, which holder is threaded to correspond with the threads in said screw-threaded opening.

WILLIAM D. KLIPFEL.
